RUG SHAMPOO HEAD UNIT OR THE LIKE

Sheldon David Hulsh, New York, N.Y.

Application February 20, 1959, Serial No. 54,693

Term of patent 14 years

(Cl. D9—2)

I claim:

The ornamental design for a rug shampoo head unit or the like, substantially as shown.
